UNITED STATES PATENT OFFICE.

ARTHUR W. SMITH, OF NEW YORK, N. Y., ASSIGNOR, BY MESNE ASSIGNMENTS, TO UNION TYPEWRITER COMPANY, OF JERSEY CITY, NEW JERSEY, A CORPORATION OF NEW JERSEY.

TYPE-WRITING MACHINE.

1,040,042.

Specification of Letters Patent.

Patented Oct. 1, 1912.

Application filed January 16, 1912. Serial No. 671,482.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

10 My invention relates to typewriting machines and more particularly to type carriers and to means for attaching type blocks thereto.

15 The main object of the invention, generally stated, is to provide simple and efficient means for attaching type blocks to type bars or carriers, and to provide a construction which may be manufactured at a small cost and by which the type bar 20 and block may be readily and efficiently united.

25 A further object of my invention is to provide means of the character specified in which an adjustment of the type blocks on the type bars or carriers may be effected.

30 To the above and other ends which will appear from the following specification, my invention consists in the features of construction, arrangements of parts and combinations of devices which will be herein-after more fully described and particularly pointed out in the appended claims.

35 In the accompanying drawings, wherein like reference characters indicate corresponding parts in the various views, Figure 1 is a detail side view of a type bar and type block embodying my invention. Fig. 2 is a detail fragmentary side view of the same with parts sectioned away, the section 40 being taken on a line $v-v$ of Fig. 4 and looking in the direction of the arrows at said line. Fig. 3 is a transverse sectional view of the same taken on a line $u-u$ of Fig. 2 and looking in the direction of the 45 arrows at said line. Fig. 4 is a detail top plan view of a type block constructed in accordance with my invention. Fig. 5 is a fragmentary detail side view of a modified form of type bar and type block with parts sectioned away, the section being taken on a line $w-w$ of Fig. 7 and looking in the direction of the arrows at said line. The view shown in Fig. 5 corresponds to that represented in Fig. 2, except that Fig. 5 50 shows a modified form of construction.

Fig. 6 is a transverse sectional view of the parts shown in Fig. 5, the section being taken on a line $x-x$ in Fig. 5 and looking in the direction of the arrows at said line. Fig. 7 is a top plan view of the type block 60 shown in Figs. 5 and 6. Fig. 8 is a top plan view of a still further modified form of construction. Fig. 9 is a transverse sectional view of the parts represented in Fig. 8, the section being taken on the line $y-y$ 65 of Fig. 8 and looking in the direction of the arrows at said line.

The type carrier 1 in the present instance is shown as a type bar stamped from sheet metal and having parallel sides and a pivot 70 opening 2 therein and an opening 3 by which connection may be made between the type bar and suitable type bar actuating devices.

Referring to Figs. 1, 2, 3 and 4, it will be 75 seen that the upper or front edge of the type bar is flat or straight at points 4 and that intermediate these flat portions are upwardly extending integral lugs, studs or projections 5 which extend from the front 80 edge of the bar. The thickness of these lugs 5 in the first instance corresponds to the thickness of the type bar or to that portion of the type bar which is received in the type block. In Fig. 2 there are two of these lugs 85 5 but the number of lugs may be varied. The type block 6 is slotted longitudinally at 7 on the under or rear side thereof, or on that side which is opposite the types or 90 printing faces 8. The slot is formed in the block by a milling operation, the slot bifurcating the block and providing two arms or side members 9 with parallel inner side walls spaced apart to correspond to the thickness of the metal from which the type bar is made at the end thereof to which the type block is affixed. In other words, the width of the slot 7 in the type block is 95 such that it will receive with a snug fit the front edge of the type bar when the block straddles the bar, as shown in Figs. 2 and 3. One or more openings 10 extend transversely through the type block, the number of such openings depending on the number of studs or lugs 5 that are provided on the type bar. As shown in Figs. 2 and 4 there are two studs 5 provided on the front edge of the bar, and a corresponding number of openings 10 are provided to receive said 100 studs when the block is in place on the bar. 105

110

From an inspection of Fig. 2 it will be understood that each lug 5 is smaller, considered in the direction of the length of the type bar, than the opening 10 in which it is received. By this arrangement a limited extent of adjustment of the type block on the type bar, and longitudinally of the latter, may be effected before the block is secured in place; whereas each side member 9 of the type block bears against the side of the type bar to prevent any lateral movement of the block relatively to the bar but afford an adjustment of the block longitudinally of the bar. When the type block has been placed in position straddling the bar as shown, and with the portions 5 of the type bar received in the openings 10 in the block, after the block is adjusted to proper position on the bar, a suitable tool may be employed to expand the metal from which each projection 5 is formed, so as to provide a head or laterally extending bur 11 which overlaps the type block and closes the mouth of the corresponding opening 10, as shown in Fig. 3. This causes the type bar and block to interlock with each other and causes the type block to be securely fastened to the bar. It will be understood that when each projection 5 on the type bar is headed, as at 11, to close the associate opening 10 in the manner described, the type block will be securely held against detachment from or movement on the bar. The bottom wall of the longitudinal slot 7 in the block will at this time be firmly held against the flattened portions 4 on the type bar. In short the body portion of the block bears against the front edge of the bar so that there is no tendency to dislodge the block from the bar nor to strain and loosen the headed connection by the impact of the block against the platen. Moreover, it will be understood that the openings 10 in the type block extend at substantially right angles to the length of the slot 7 therein, so that the projections 5 limit the sliding adjustment of the block longitudinally of the bar, and prevent the block from being withdrawn from the bar longitudinally thereof.

In Figs. 5, 6 and 7 I have shown the modified form of construction in which the openings 10^a extend to the front face 12 of the type block 6^a, and the inner walls of each opening 10^a are inclined upwardly and outwardly at the upper portions thereof, as indicated at 13 in Fig. 6. Each stud, lug or projection 5^a which is received within an opening 10^a extends to a point where it is flush with the front face 12 of the block.

After the block is inserted in place on the bar 1^a, and adjusted longitudinally thereof, a suitable tool may be employed to expand the metal from which the projections 5^a are formed, as indicated in Fig. 6. If desired, the metal of the projections 5^a may be split

or indented, as indicated at 14, in order to facilitate a spreading of the metal laterally into engagement with the inclined walls 13 in the type block to thus effectively secure the type block to the bar with an interlocking engagement.

In each of the constructions shown in Figs. 1 to 7 inclusive, I have illustrated three types 8 or 8^a on a bar and two fastening studs 5 or 5^a which connect each block 75 to its bar. In Figs. 8 and 9 I have shown a type block 6^b provided with but two types 8^b. In this construction a single opening 10^b extends transversely through the type block and receives a stud, lug or projection 80 5^b which extends from the front edge of the type bar 1^b and is headed or riveted over the mouth of the opening 10^b, as indicated at 11^b, to effect an interlocking engagement between the type bar and type block. Like 85 the constructions shown in the preceding figures the type block shown in Figs. 8 and 9 is slotted to receive and straddle the type bar. In this modified form of construction, like those shown in the preceding figures, 90 the stud 5^b is smaller, considered longitudinally of the type bar, than the opening 10^b in which it is received, so as to afford an adjustment of the type block on the type bar longitudinally of the latter. Moreover, 95 the integral stud 5^b on the type bar is received in an opening in the type block 6^b intermediate the types thereon.

From the foregoing description it will be understood that I have provided simple and 100 efficient means for effectively connecting a type block to a type bar or carrier and that the construction is such that it enables the parts to be made at comparatively small cost and there is no liability of a type block being accidentally displaced on or from the bar after the block is secured in place. It will be seen that the type bar, the type block and the means by which the two are connected comprise only two members, the block 110 and the bar, and that these two members are formed for interlocking engagement with each other in such a manner that the block may be rigidly secured to the bar. There are no screws or threaded connections for 115 attaching one member to the other and the simplicity of the construction enables it to be made at small cost without, however, detracting from the effectiveness of the construction.

Various changes may be made without departing from the spirit and scope of my invention.

What I claim as new and desire to secure by Letters Patent, is:—

1. The combination of a type bar; and a type block, the body of the type block bearing against the body of the type bar and one of said members having an opening therethrough and the other member having 130

- an integral part that extends through said opening and is enlarged at the mouth of the opening to form an interlocking engagement between the type bar and the type block.
2. The combination of a type bar; and a type block, the type block having an opening that extends transversely therethrough, and the type bar having an integral part that extends through said opening and is headed at its end to effect an interlocking engagement between the type block and type bar.
3. The combination of a type bar; and a type block having an opening therethrough and through which a part of the type bar extends, the said part of the type bar being expanded or headed over the opening to prevent a detachment of the type block from the bar.
4. The combination of a type bar having an integral stud; and a type block having an opening extending transversely therethrough and through which opening said stud extends, the end of said stud being headed at the mouth of the opening to prevent a detachment of the type block from the bar.
5. The combination of a type bar having an integral stud; and a type block having a plurality of types thereon and having an opening which extends transversely through the block between types thereon, said stud being expanded at the mouth of said opening to prevent a detachment of the block from the bar.
6. The combination of a type bar having an integral stud; and a type block having an opening extending transversely therethrough and through which opening said stud extends, said stud being smaller than the hole in which it is received to afford a limited adjustment of the block on the bar, and the end of the stud being headed at the mouth of the opening to prevent a detachment of the block from the bar.
7. The combination of a type bar having an integral stud; and a type block bifurcated to straddle the bar and having an opening extending transversely through the block, the stud being received in said opening and being headed at the outer end thereof to prevent a detachment of the block from the bar.
8. The combination of a type bar having an integral stud; and a type block bifurcated to straddle the bar and having an opening extending transversely through the block, the stud being smaller than said opening to afford a limited adjustment of the block on the bar, and the stud being headed at the mouth of the opening to prevent a detachment of the block from the bar.
9. The combination of a type bar having an integral stud; and a type block bifurcated to straddle the bar and having an opening extending transversely through the block at substantially right angles to the length of the slot formed by the bifurcation in the block, the stud being smaller or shorter in the direction of the length of the bar than the length of the said transverse opening to afford a limited adjustment of the block longitudinally of the bar, the end of the stud being expanded at the mouth of said opening to prevent a detachment of the block from the bar.
10. The combination of a type bar having an integral stud; and a type block bifurcated to straddle the type bar and having a plurality of types thereon, said block also having an opening between types, which opening extends transversely through the block at substantially right angles to the length of the slot formed by the bifurcation in the block, the said stud extending into said opening and being smaller, considered longitudinally of the bar, than the transverse opening to afford a limited adjustment of the block on the bar, and the stud being expanded at the mouth of the opening in the block to prevent a detachment of the block from the bar.
11. The combination of a type bar having parallel sides at the end where the block is connected with the bar, and also having an integral lug projecting from the upper or front edge of the bar; and a type block which is slotted to receive the parallel sided portion of the bar and has a transverse opening therethrough to receive the stud on the edge of the bar, said stud being expanded at the mouth of the opening in the block to prevent the block from being detached from the bar.

Signed at the borough of Manhattan, city of New York, in the county of New York, and State of New York, this 15th day of January, A. D. 1912.

ARTHUR W. SMITH.
